UNITED STATES PATENT OFFICE.

MILTON BARTLEY, OF POLK, PENNSYLVANIA, ASSIGNOR OF THREE-TENTHS TO JAMES MOORHEAD MURDOCH AND HARRY FLEMING McDOWELL, OF PITTSBURG, AND GEORGE LINCOLN WEAVER, OF PHILADELPHIA, PENNSYLVANIA.

NUT-LOCK.

SPECIFICATION forming part of Letters Patent No. 656,151, dated August 14, 1900.

Application filed February 9, 1900. Serial No. 4,640. (No model.)

To all whom it may concern:

Be it known that I, MILTON BARTLEY, a citizen of the United States, residing at Polk, in the county of Venango and State of Pennsylvania, have invented certain new and useful Improvements in Nut-Locks, of which the following is a specification, reference being had to the accompanying drawings, forming part of this specification, in which—

10 Figure 1 is a partial side elevation of a rail-joint, illustrating the application of my nut-lock. Fig. 2 is a cross-sectional view indicated by the line II II of Fig. 1. Fig. 3 is a horizontal sectional view taken on the line 15 III III of Fig. 1. Figs. 4 and 5 are perspective views of the lock detached.

My invention consists of an improvement in devices for preventing nuts from loosening by turning, and is designed to embrace 20 the sides of the nut and to be held in immovable engagement with the fish-bar or other member upon which the nut is secured. I have shown it applied to the well-known rail-joint, which is one of the chief sources of 25 trouble with loose nuts.

Referring now to the drawings, 2 is the rail, the ends of which are connected by the usual fish-plates 3 and bolts 4. Extending upwardly from the bolt-hole of the fish-plate on 30 one outer side is a depression or groove 5, which may, however, be made in other directions, if desired, although I prefer the position indicated for the reason that the groove is thus located immediately under the edge 35 of the rail-head and for the further reason that the effect of gravity is thus utilized to maintain the lock in position.

The lock consists of a rectangular clasp made of a band or bar of metal having a mid- 40 dle portion 6 and side portions 7 and 8, so arranged parallel to each other as to embrace the sides of the nut when the lock is in position. Either or both of the sides 7 and 8 is made sufficiently long to project beyond the 45 corner of the nut and to be bent around it, as clearly shown in Fig. 1. Extending outwardly and downwardly from the back of the

clasp is a lug 9, adapted to fit into the groove 5, and when the clasp is placed on the nut and this lug is driven into place, as shown, 50 it will be seen that the clasp will be prevented from turning and likewise the nut. To further insure its holding action, the extended end of one or both of the side pieces may be turned around the corner of the nut by a 55 blow of a hammer, as shown at 10. When thus in position, the lock will positively hold the nut against movement and will be found to be an efficient, simple, and reliable lock to prevent dislodgment of the nut. Its removal is easily effected by turning out the end 10 and prying the clasp out of engagement with the groove, when the nut may be removed.

The lock may be made of forged iron or 65 malleable casting, while the grooves 5 may be rolled or pressed in the fish-bar originally or may be easily made by suitable tools on old bars already in position.

The advantage of my invention will be appreciated by those skilled in the art, as it is very simple, easy to make and use, cheap in cost, and reliable in action, and in actual service has demonstrated its efficiency for an extended length of time. 70

Having described my invention, what I claim is—

1. A nut-lock consisting of a rectangular clasp, one or both sides of which are adapted to be bent around the corner of the nut, and 80 a lug projecting outwardly from the back, and with an inwardly-extending face on a plane with the inner edges of the clasp, substantially as set forth.

2. In combination with a fish-plate provided with a retaining-groove, a rectangular clasp adapted to embrace the sides of a nut, and a backwardly-projecting lug adapted to engage the retaining-groove and to bear against the inner face of the nut, substantially as set forth. 85

3. In a nut-lock, the combination of a fish-plate or member provided with a bolt-hole, a groove in the face of the plate extending out-

wardly from the bolt-hole, a clasp formed of a flat metallic bar bent to conform to the sides of the nut and to be bent around its corner, and provided with a backwardly-projecting lug in engagement with the groove and held therein by the inner face of the nut, substantially as set forth.

In testimony whereof I affix my signature in presence of two witnesses.

MILTON BARTLEY.
